UNITED STATES PATENT OFFICE.

ERNEST F. RUECKERT, OF PROVIDENCE, RHODE ISLAND, ASSIGNOR TO JOHN HOOD, OF SANTA ROSA, CALIFORNIA.

DESIGN FOR A SPOON.

No. 37,724.

Specification for Design.

Patented Dec. 12, 1905.

Application filed October 28, 1905. Serial No. 284,916. Term of patent 14 years.

To all whom it may concern:

Be it known that I, ERNEST F. RUECKERT, a citizen of the United States, residing at the city of Providence, in the county of Providence and State of Rhode Island, have invented a new, original, and ornamental Design for a Spoon, as set forth in the following specification and illustrated in the accompanying drawing.

The drawing is a face view showing the design of the spoon.

I claim—

The ornamental design for a spoon, as shown.

ERNEST F. RUECKERT.

Witnesses:

HOWARD E. BARLOW,
E. I. OGDEN.
